Patented Oct. 31, 1922.

Inventor:

V. Sfetescu,
By Marshal Clark
Attest.

UNITED STATES PATENT OFFICE.

VASILE SFETESCU, OF WEISSENSEE, NEAR BERLIN, GERMANY.

AIR-COOLED CYLINDER FOR ENGINES WITH ONE OR MORE CYLINDERS.

Application filed March 24, 1922. Serial No. 546,490.

To all whom it may concern:

Be it known that I, VASILE SFETESCU, a citizen of the Republic of Rumania, residing at Weissensee, near Berlin, Germany, have invented certain new and useful Improvements in Air-Cooled Cylinders for Engines with One or More Cylinders, of which the following is a specification.

This invention relates to internal combustion engines and more particularly to internal combustion engines of the air cooled type.

The primary object of the invention is to secure perfect carburetion, intensive utilization of the gas mixture and a reduction in fuel consumption.

A further object of the invention is to provide an engine in which the explosive mixture in unheated condition is led directly onto a portion of the wall of the combustion chamber of the cylinder, so that said mixture will tend to cool said portion, while at the same time said portion of the combustion chamber of the wall will tend to heat the explosive mixture and thus vaporize the fuel.

With the foregoing objects outlined and with other objects in view which will appear as the description proceeds, the invention consists in the novel features herein-after described in detail, illustrated in the accompanying drawing and more particularly pointed out in the appended claim.

The accompanying drawing shows a vertical sectional view of the upper portion of one of the improved engine cylinders.

In the drawing *e* designates the cylinder of an internal combustion engine of the air cooled type. The interior of this cylinder merges into a combustion chamber *d*, and this combustion chamber communicates with a passageway *c*. The combustion chamber and passageway have an upper wall or head *d'*, which is preferably integral with the cylinder. This passageway *c* extends laterally from the axis of the cylinder and at its outer end communicates with ports *c'* and *g'*, which are controlled respectively by the intake valve *c* and the exhaust valve *g*. The port *g'* communicates with the exhaust gas passageway *f* while the port *c'* communicates with the

passageway *c* which extends from a position surrounding the axis of the cylinder to said inlet port *c'*. The passageway *c* communicates with a vertically arranged passageway *a* which communicates with the interior of an intake tube *c*, that receives the explosive mixture from the carburetor (not shown). The tube *c* is connected to the wall of the intake passageway. The wall *d'* is arranged between the passageway *c* and the passageway *c* and combustion chamber, and is provided with a valve *h*.

In operation the explosive mixture from the carburetor passes into the intake tube *c* and is then directed downwardly through the vertically arranged passageway *a* onto the wall *d'*, so that said wall is cooled by the mixture. As the mixture continues along the passageway *c* it cools other portions of said wall and is itself heated by said wall. When the mixture passes through the port *c'* the fuel is in vaporized condition and it is further heated as it passes into the combustion chamber *d*. The charge is ignited by a spark plug (not shown) arranged in the aperture *h*, and the exhaust gases may pass off by way of the port *g* and passageway *f*.

Owing to the fact that the explosive mixture entering the engine is constantly cooling the wall *d'*, the explosive mixture in the combustion chamber will be prevented from self-ignition.

From the foregoing, it is believed that the construction, operation and advantages of the invention may be readily understood by those skilled in the art, and it is apparent that changes may be made in the construction illustrated without departing from the spirit of the invention as expressed in the claim.

What I claim and desire to secure by Letters Patent is:

In an internal combustion engine, an air cooled cylinder provided with an integral head, a horizontally disposed laterally extending passageway arranged in said head and communicating with the combustion chamber of the cylinder, a horizontally disposed explosive mixture inlet passageway arranged in the head and located above the first mentioned passageway and said com-

pression chamber, a partition wall arranged between the inlet passageway and the combustion chamber and first mentioned passageway adapted to be heated by the gases of combustion and cooled by the explosive mixture on its way to the combustion chamber, and means for directing the explosive mixture entering said inlet passageway onto the partition wall in the direction of

the axis of the cylinder in order to concentrate said mixture on said partition wall. 10

In testimony whereof I affix my signature in presence of two witnesses.

VASILE SFETESCU.

Witnesses:

ROBERT HEIN,
E. HOLTZERMAN.
